US0D1090155S

(12) **United States Design Patent** (10) **Patent No.:** **US D1,090,155 S**
(45) **Date of Patent:** **** Aug. 26, 2025**

(54) **MULTIMODE COOKER**

- (71) Applicant: **SharkNinja Operating LLC**, Needham, MA (US)
(72) Inventor: **Joyce Chien Tu**, Melrose, MA (US)
(73) Assignee: **SharkNinja Operating LLC**, Needham, MA (US)
(**) Term: **15 Years**
(21) Appl. No.: **29/978,681**
(22) Filed: **Dec. 13, 2024**

Related U.S. Application Data

- (60) Continuation of application No. 29/923,009, filed on Dec. 27, 2023, now Pat. No. Des. 1,056,608, which is a continuation of application No. 29/891,185, filed on May 2, 2023, now Pat. No. Des. 1,015,810, which is a division of application No. 29/806,542, filed on Sep. 3, 2021, now Pat. No. Des. 988,778.
